United States Patent Office

Des. 181,664
Patented Dec. 10, 1957

181,664

DUST FILTER

Hans Müller, Zurich, Switzerland, assignor to Aerosol
Corporation T. R., Vaduz, Liechtenstein

Application October 3, 1955, Serial No. 38,214

Term of patent 7 years

(Cl. D46—1)

The figure is a perspective view of a dust filter, showing my new design in which the side not shown is like the side shown.

I claim:

The ornamental design for a dust filter, as shown and described.
